HOUSING FOR A STEREOPHONIC LOUDSPEAKER

Gary I. Elwell, 821 W. Roseburg Ave.,
Modesto, Calif. 95350

Filed June 25, 1974, Ser. No. 483,020

Term of patent 14 years

Int. Cl. D14—01

U.S. Cl. D26—14 G

FIG-1

FIG-2

FIG-3

FIG-4

FIG. 1 is a front perspective view of a stereophonic loudspeaker, showing my new design;

FIG. 2 is a rear elevation on a reduced scale;

FIG. 3 is a side elevation of the same; the sides being alike; and

FIG. 4 is a top plan view thereof.

I claim:

The ornamental design for a housing for a stereophonic loudspeaker, as shown and described.
